UNITED STATES PATENT OFFICE.

JOHN FARRAR, OF LEEDS, ENGLAND.

GUARD FOR PLATEN PRINTING-PRESSES.

No. 927,226.

Specification of Letters Patent.

Patented July 6, 1909.

Application filed June 23, 1908. Serial No. 439,931.

To all whom it may concern:

Be it known that I, JOHN FARRAR, of Leeds, in the county of York, England, a subject of the King of Great Britain, have 5 invented certain new and useful Improvements in Guards for Platen Printing-Presses, of which the following is a specification.

In feeding platen printing presses, accidents frequently happen to the attendants 10 who through carelessness or otherwise, fail to lift the hands before the platen reaches the type bed; and with a view to preventing such accidents, various contrivances, such 15 as hinged flaps and pivoted guards, have hitherto been provided wherein the motion of the platen is caused to operate said contrivances to automatically thrust up the hand out of the way.

20 Now this invention refers to an improved guard of the pivoted type, as hereinafter described, which is operated by the motion of the platen in such a manner as to cause the said guard to have a movement greater and 25 so as to act more efficiently than guards hitherto employed; while at the same time, the construction of the guard is such as to enable it to be produced at a cheap cost and also capable of being readily applied to any 30 press in which the platen swings to and from a type bed.

According to this invention I employ a frame which is mounted over the free edge of the platen and securely attached to the opposite sides thereof, said frame being formed 35 with upstanding lugs carrying a horizontal shaft provided with a tilting plate, which latter, when the platen is in the open position, lies in the same plane as the platen. 40 The shaft which carries the tilting plate is projected outward beyond one end of the said plate, and on the projecting portion of the shaft is mounted a chain wheel. To this chain wheel, one end of a chain is suitably at- 45 tached and the other end of the chain is connected to a stud provided on the frame of the machine, the parts being so connected that during the time the platen is moving toward the type bed, the chain has the effect of par- 50 tially rotating the chain wheel and its shaft, so as to raise or rotate the tilting plate from its normal position through approximately a half revolution against the hand of the attendant which is thus automatically thrust 55 or lifted out of the way of the closing platen, and on the shaft of the tilting plate, I em-

ploy a spring or other similar means adapted in the return movement of the platen to move the tilting plate in the reverse direction so as to bring the same back to its normal 60 position when it is in substantially the same plane as the platen.

In the drawing, Figure 1 is a side elevation illustrating my improved guard for platen printing presses and Fig. 2 is a plan 65 of the same.

Referring particularly to the drawing, I employ a frame 1 which is mounted over the free edge of a platen 2 and securely attached to the opposite sides thereof by screws 3, and 70 this frame 1 is formed with upstanding lugs 4 which carry a horizontal shaft 5 to which is connected a tilting plate 6. This tilting plate 6 when the platen 2 is in its open position, lies in the same plane as the platen and 75 the shaft 5 is provided at one end with a chain wheel 7 connected to which in any suitable place and in any suitable manner, is a chain 8, the opposite end of the chain 8 being connected to a stud 9 provided on the 80 frame 11 of the press, 12 indicating a shaft also mounted in the frame of the machine and upon which the platen 2 swings.

On the shaft 5 and preferably adjacent to the chain wheel 7 I employ a helical spring 85 16 so connected to the moving parts as to normally maintain the tilting plate 6 in its normal position substantially in the same plane as the platen 2. It will now be apparent that as the platen 2 swings up to 90 toward the type bed of the press, the chain 8 will be drawn taut in the initial movement of the platen and will then rotate the chain wheel 7 to swing the tilting plate 6 upwardly 95 to produce the desired result in thrusting the operator's hand or hands away from the moving platen and as hereinbefore stated, in the return movement of the platen, the spring 16 will operate to return the tilting plate to 100 its normal position.

I claim as my invention:

In pivoted guards for platen printing presses, the combination with a swinging platen, of a frame extending outwardly and over the free edge of the platen, a shaft 105 mounted in said frame, a tilting plate connected to said shaft and extending downwardly within said frame so as to normally lie in the same plane as the platen, a chain wheel on said shaft, a chain attached thereto 110 and to the frame of the machine for partially rotating the shaft automatically when the

2
platen moves toward the type bed so as to raise or rotate the tilting plate through about one-half a revolution, and a spring on said shaft for rotating it automatically in the reverse direction on the return movement of the platen so as to return the tilting plate to its normal position.

In witness whereof I have hereunto set my hand in the presence of two witnesses.

JOHN FARRAR.
